UNITED STATES PATENT OFFICE

ELMER W. BELLUCHE, OF RACINE, WISCONSIN, ASSIGNOR TO CHRISTENSEN MACHINE COMPANY, OF RACINE, WISCONSIN, A CORPORATION OF WISCONSIN

SIGNATURE STITCHING MACHINE

Application filed January 29, 1930. Serial No. 424,266.

This invention relates to certain new and useful improvements in signature stitching machines and refers more particularly to the delivery mechanism thereof.

5 The delivery mechanism of signature stitching machines usually embodies a table having a moving belt or plurality of belts onto which the signatures are discharged and which is intermittently advanced upon each 10 operation of the delivery mechanism to carry the signatures which are deposited thereon one above the other in staggered relation forwardly to suitable receiving means. It is, of course, desirable that the pile of books on 15 the table be maintained even and continuous, but heretofore no means has been provided for regulating the drive of the delivery table belt or belts and as signatures are not always discharged upon each successive cycle of 20 operation, this has been impossible.

It is, therefore, an object of this invention to co-ordinate the drive of the delivery table conveyer belts with the delivery mechanism per se so that it functions only when a signature is actually discharged.

Another objection to existing delivery mechanisms was the lack of means for timing the advance of the delivery table belts, to accommodate signatures of different 30 widths. It is obvious that narrow books are completely discharged onto the delivery table belts quicker than books of greater width, and as no means of regulating the time of feed of the delivery table belts was provided, difficulty was encountered in maintaining the proper cooperation between the 35 rate of discharge of the books from the delivery mechanism per se and the movement of the delivery table belts.

40 It is, therefore, another object of this invention to provide a novel and simplified means for regulating the time of operation of the delivery table belts together with 45 means for regulating the amount of feed. With this structure, it is possible to at all times have the best operating condition, or in other words, to have the feed for the table belts begin just as the tail edge of the book 50 leaves the delivery mechanism.

Another objectional feature of delivery mechanisms heretofore in use with signature stitching machines, is the fact that when rather thick books are handled, there is a tendency for the book to follow the discharge 55 rollers and turn under, due to the angle of the delivery tapes, and to overcome this objection the present invention contemplates as another of its objects the provision of means for readily adjusting the discharge angle of 60 the delivery tapes so that the mechanism may be adjusted to efficiently handle books of different thicknesses.

In connection with the discharge of the books it is also an object of this invention to 65 provide means for holding the free ends of the books down so that the discharging signatures are thrown on top of, rather than between, the covers of the books already on 70 the delivery table.

A more specific object of this invention resides in the provision of means controlled by the passage of signatures therewith during their normal discharge from the machine, for controlling the operation of the delivery table 75 belt drive so that the same functions only when a signature is actually being discharged.

And a further object of this invention is to improve and simplify the general construction of delivery mechanisms for signature stitching machines and the like.

With the above and other objects in view, which will appear as the description proceeds, my invention resides in the novel construction, combination and arrangement of parts substantially as hereinafter described and more particularly defined by the appended claims, it being understood that such changes in the precise embodiment of the 85 herein-disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a perspective view of a portion 100 of a delivery mechanism for a signature

stitching machine embodying this invention, and illustrating the delivery table and its relation to the delivery mechanism per se;

Figure 2 is an enlarged detail view illustrating the mechanism for controlling the delivery table belt drive;

Figure 3 is an enlarged detail front view of the structure shown in Figure 2;

Figure 4 is a view somewhat similar to Figure 2 with the parts in another position and with portions broken away to illustrate structural details;

Figure 5 is a detail, sectional view taken through Figure 1 on the plane of the line 15 5-5;

Figure 6 is a cross sectional view taken through Figure 5 on the plane of the line 6-6, and

Figure 7 is a fragmentary, detail view taken through Figure 1 on the plane of the line 20 7-7.

Referring now more particularly to the accompanying drawings, in which like numerals designate like parts throughout the several views, numerals 5 and 6 represent the end or supporting walls of a delivery mechanism for use with a conventional signature stitching machine or the like, and between which the delivery mechanism per se is mounted. As this invention is directed only to the delivery mechanism, no part of the signature stitching machine is shown but reference may be had to Patent No. 1,351,231 for a typical illustration of a machine with 30 which the structure of this invention may be used.

As is well-known, the signatures after being stitched are conveyed along a saddle structure 7, indicated by dotted lines in Figures 2 and 4, until they are wholly between the walls 5 and 6 and in line with the delivery mechanism mounted therebetween. A tucker blade 8 then elevates the signature upwardly between a delivery roll 9 consisting of a plurality of pulleys constantly rotating on a shaft 10, and delivery tapes 11 trained over the pulleys 9 and traveling in unison therewith.

The signature is gripped between the pulleys and their cooperating tapes 11 and carried upwardly and forwardly to be discharged onto a delivery table, indicated generally by the numeral 12.

The tapes 11, as is customary, are trained about lower pulleys 13, upper idler pulleys 14 by which they are maintained under the proper degree of tension, and over forward pulleys which in the present instance are replaced by an adjustable shaft 15, to be later described.

The delivery table 12 consists of side supporting bars 16 which have their inner ends hingedly connected with the walls 5 and 6 in any suitable manner, as by a shaft 17 which extends across the distance between

the walls 5 and 6 and has its end portions passed through the bars and journaled in suitable bearings 18 formed in the walls and its medial portion enlarged to provide a plurality of belt receiving pulleys 19. The outer ends of the side bars 16 may be supported in any suitable manner as by having diagonal braces 20 connected at one end with the side bars and at their lower ends with the walls 5 and 6.

The outer ends of the bars 16 are connected by a roller 21 whose medial portion, like that of the shaft 17 is provided with a plurality of belt receiving pulleys in line with the pulleys 19, and whose ends are journaled in bearings formed in sliding bearing blocks 22. The blocks 22 have outwardly extending spaced flanges between which the side arms 16 are slidably received, and are rigidly connected by a shaft 23 whose ends are clamped in suitable split bearings 24 formed in the outer portions of the blocks 22.

Tie rods 25 also extend between the side bars 16 to maintain them in proper spaced relation and the outermost bar 25 forms a support against which tensioning screws 26 carried by the blocks 22 abut to provide means for forcing the blocks and consequently the roller 21 outwardly to tighten the endless belts 27 trained about the pulleys of the shaft 17 and the roller 21.

The belts 27 form the work receiving surface of the delivery table and if desired may be replaced by a single belt sufficiently wide to extend across the entire width of the table. However, it has been found that separated belts are more easily maintained in proper alignment. To support the medial portion of the belts 27, a plate 28 extends across and is secured to the tie rods 25.

The signatures, as they leave the delivery mechanism per se, are discharged onto the delivery table belts and by intermittently advancing the belts, are constantly moved forward in a staggered relation, as clearly illustrated in Figure 1, until the leading signatures reach the discharge ends of the delivery table belts. The signatures may then be discharged directly into any means of conveyance or may be permitted to accumulate upon an end plate 28', as will be readily apparent.

Heretofore, it has been customary to merely provide an intermittent drive for the forward movement of the delivery table belts which functioned upon each operation of the delivery mechanism whether a signature was present or not, and as very often the machine is permitted to operate without passing signatures therethrough, it is readily apparent that the condition of the pile upon the delivery table was not even nor continuous.

To eliminate this objectionable feature, the present invention contemplates novel means for driving the delivery table belts so that

- the belts are moved only when a signature is actually being discharged. To carry out this object, the shaft 17 which forms the drive means for the delivery table belts, has one end extended beyond the bearing bushing 18 carried by the wall 5 and has a ratchet wheel 29 pinned or otherwise fixed thereto with which a pawl 30 cooperates whenever it is desired to advance the delivery table belts.
- 10 The pawl 30 is pivoted to the outer end of an arm 31, as at 32, which extends from a sleeve 33 freely journaled upon the outer end of the shaft 17. The sleeve 33 has its portion directly adjacent the arm 31 slightly enlarged in diameter to receive a pinion 34 which, to prevent turning with respect to the sleeve, is secured to the arm 31 and the flange which forms the base thereof by rivets 35.
- 15 Meshing with the pinion is a rack 36 formed on the outer end of a pitman 37 which is maintained in its proper position by a member 38 freely journaled on the outer end of the sleeve 33 and having an elongated tubular portion 39 in which the pitman outer end is freely slideable and a central substantially circular portion 40 which surrounds the pinion gear and forms a guard housing therefor. The pitman is thus maintained in proper meshed relation with the pinion gear and is free to be reciprocated by means to be later described, to oscillate the pinion gear and consequently the arm 31 to carry the pawl back and forth as will be readily apparent.
- 20 During forward movement of the pawl, the ratchet wheel 29 and consequently the shaft 17 will be rotated to advance the delivery table belts whenever the pawl is engaged with the teeth of the ratchet wheel to which position the pawl is normally yieldably urged by a contractile spring 41 connected at one end with the free end of the pawl and at its other end with a screw 42 carried by the flange forming the base of the arm 31. However, as it is desirable to drive the delivery table belts only when a signature is actually being discharged, the engagement of the pawl with the ratchet wheel is controlled by the discharging signatures in a manner to be later described, through a mask 43 over which a roller 44 carried by the pawl tracks.
- 25 The mask 43 is substantially semi-circular in shape and is of such diameter that when in its operative position it maintains the nose of the pawl out of engagement with the ratchet wheel teeth throughout the entire range of movement of the pawl.
- 30 The mounting for the mask consists of an approximately U shaped lever 45 medially pivoted from the wall 5, as at 46, and having a roller 47 which tracks on a cam 48 having a high and a low period of dwell, to raise and lower the lever and move the mask to and from operative position, a weight 49 carried by the lever maintaining it in position engaging its roller with the cam.
- 35 The cam 48 forms a central annular flange of a rotatable disc 50 to which the pitman 37 is connected, as at 51, to be reciprocated thereby, and to enable the length of the pitman stroke and consequently the amount of feed of the delivery belts to be regulated, in accordance with the width of the books, the connection between the pitman 37 and the disc 50 is adjustable. A substantially T shaped slot 52 formed in the disc to slidably receive the head of the pivot pin 51 which may thus be secured at any desired distance from the center of the disc, forms the adjustable connection between the disc and the pitman.
- 40 The rotation of the disc and cam reciprocates the pitman to carry the pawl back and forth and rocks the lever 45 to move the mask to and from operative position, the alignment of the low portion of the cam with the roller 47 permitting the weight 49 to rock the lever in a clockwise direction with respect to Figures 1 and 2, to lower the mask out of operative position and allow the pawl to move the ratchet wheel forward. The drive for the pawl and the operation of the mask are thus positively coordinated, and to enable the performance of these functions to be properly timed with the discharge of the signatures from the delivery mechanism per se, the disc is rotatably adjustably connected with its driving means.
- 45 The driving means for the disc also mounts the same and consists of a shaft 53 journaled in a bearing formed in the wall 5 (see Figure 5) and to which the disc is adjustably connected by being clamped to a flange 54 on the shaft by means of screws 55 passed through counterbored apertures in the disc and threaded into nuts 56. The nuts 56, as best illustrated in Figure 6, have flattened portions receivable between the outer periphery of the flange 54 and the inner periphery of an inwardly directed flange 57 on the disc 50 to hold the same against turning during tightening of the screws 55, as will be readily obvious.
- 50 Rotation is imparted to the shaft by means of a gear 58 secured on the inner end of the shaft 54 and meshed with a pinion 59 fixed on the delivery roll shaft 10, which also carries a gear 60 by which the delivery mechanism receives its drive from the stitching machine in any desired manner, not shown.
- 55 Again referring to the control for the drive of the delivery table belts by means of the cam 48, it is seen that the relation of the high portion of the cam 48 to the slot 52 in which the pin 51 is mounted is such that when the pitman reaches its fully extended position and begins its return stroke the roller 47 will just leave the high portion of the cam and permit the pawl to engage the teeth of the ratchet wheel so that the following movement of the pitman produces a forward movement

of the ratchet wheel and the shaft 17 connected therewith.

The mechanism so far described, however, is independent of the actual discharge of signatures from the delivery mechanism, and as it is desirable to prevent the operation or drive of the delivery table belts except when a signature is actually discharged, means are provided for co-ordinating the operation of the lever 45 which controls the mask, with the delivery mechanism per se so that the mask will be maintained in its operative position preventing the engagement of the pawl with the ratchet wheel whenever a signature is not discharged.

This means consists of a plurality of fingers 61 secured to a shaft 62 journaled in the walls 5 and 6, and having their free ends extended downwardly and forwardly between adjacent rollers 14 to lie in the path of the discharging signatures carried between the peripheral edges of the pulleys 9 and the tapes 11, whereby the passage of a signature raises the free ends of the lever to slightly oscillate the shaft 62.

The end of the shaft 62 which extends beyond the wall 5 has a dog 63 secured thereto whose lower end is stepped, as at 64, to cooperate with a stop 65 carried by the adjacent free end of the lever 45 so that when the fingers 61 are in their normal position and hang down beneath the path of the discharging signatures the stepped end 64 of the dog will be directly above the stop 65, to prevent the lever 45 from turning about its mounting 46 when the lower part of the cam registers with the roller 47.

In this manner, operation of the delivery table belt drive is prevented except when the fingers 61 are raised by the passage of a signature therebeneath.

As hereinbefore stated, the timing of the delivery table belt drive is governed by the width of the signatures being handled and is determined from the trailing edge of the book, as the leading edge reaches the fingers 61 at the same time irrespective of the width of the book.

The position of the disc 50 is, therefore, adjusted so that the lower part of the cam reaches the roller 47 before the trailing edge of the book passes from beneath the ends of the fingers 61 to permit the lever 45 to rock and raise its stop 65 before the stepped end of the dog 63 is again allowed to return to its normal position above the stop. With this adjustment each advance of the delivery table belts begins at approximately the same time the books are discharged from between the pulleys 9 and the tapes 11 so that they strike a moving rather than a stationary surface and thus insure more efficient handling.

Heretofore it has been found that when relatively heavy books were being handled there was a tendency for their leading edge

to follow the pulleys 9 and turn under. This, of course, is objectionable as it prevents the proper discharge and stacking of the books one upon the other on the delivery table, and to overcome this feature the forward roller 15 about which the tapes 11 are trained is vertically adjustable to permit the angle formed by the stretch of the tapes between the roller 15 and the pulleys 9 to be increased when heavy books are being handled so that they are discharged in a substantially horizontal line to eliminate the tendency of their leading edges to follow the pulleys 9 and turn under.

Vertical adjustment of the roller 15 is accomplished by forming the same of a length of tubing having its ends journaled on plugs 66 to be freely rotatable thereon with the tapes 11. The plugs 66 are axially eccentrically secured to a shaft 67 freely journaled in suitable bearings formed in the walls 5 and 6 and the end of the shaft 67, which projects through the wall 6, has an adjusting member 68 secured thereto by which it and consequently the plugs 66 may be turned to raise and lower the roller 15.

The adjusting member 68 has a handle 69 and a portion provided with a segmental recess 70 in which a screw 71 is received, which upon being tightened secures the member and consequently the shaft 67 in any position of adjustment to which it may be moved by the handle. As illustrated in the drawings, the roller 15 is in its position of maximum elevation and is adjusted for books of maximum thickness. Rotation of the handle and the adjusting member 68 in a clockwise direction with respect to Figure 4 causes the roller to be moved to a lower position of adjustment.

To maintain the outer ends of the signatures flat against the table, especially where they have stiff covers which have a tendency to project upwardly and to thus prevent the signatures as they are discharged from the delivery mechanism from being thrown between the covers, a pair of wheels 72 are freely rotatably carried by arms 73 whose inner ends are freely pivotally mounted on a cross shaft 74, the arm 73 being maintained in any desired position of transverse adjustment by collars 75, as will be readily apparent. The cross shaft 74 is secured at its outer ends in upright brackets 76 which are slidable along the side arms 16 and are securable at any desired position of adjustment by tightening thumb screws 77.

From the foregoing description taken in connection with the accompanying drawings, it will be readily apparent to those skilled in the art to which an invention of the character described appertains, that I provide an improved and novel delivery mechanism for signature stitching machines and the like in which perfect co-ordination between the delivery table belts and the delivery mechanism per se is obtainable, and

in which different widths of books are readily accommodated and the tendency of heavier books to turn under is eliminated.

What I claim as my invention is:

- 5 1. In a signature stitching machine or the like, a delivery mechanism including a conveyer, means including a rotatable drum for discharging completed signatures onto the conveyer, drive means for intermittently advancing the conveyer and trip means mounted above said drum and in normal contact therewith to intermittently advance the conveyer upon a signature passing between said drum and the trip means.
- 10 2. In a signature stitching machine or the like, a delivery mechanism, including a delivery table provided with a movable conveyer, means including a rotatable drum for discharging completed signatures onto the 70 table, drive means for intermittently advancing the conveyer, and trip means normally in contact with said drum and operable upon a signature passing between the drum and the trip means whereby said conveyer is intermittently advanced when a signature is discharged.
- 15 3. In a signature stitching machine or the like, a delivery mechanism including a delivery table provided with a movable conveyer, means including a rotatable drum for discharging the completed signatures onto the table and conveyer, drive means for intermittently advancing the conveyer, a trip in normal contact with said drum whereby 80 signatures discharging around said drum pass beneath the trip and the drum whereby said trip is displaced to operate said drive means.
- 20 4. In a signature stitching machine or the like, a delivery mechanism including a delivery table provided with a movable conveyer, means discharging completed signatures onto the table and conveyer, pawl and ratchet means for intermittently advancing the conveyer and means for oscillating the pawl, means normally holding the pawl out of engagement with the ratchet to prevent its movement by the pawl to advance the conveyer, and means controlled by the discharge 85 of signatures for governing the action of the means for holding the pawl out of engagement with the ratchet whereby the passage of a signature during its discharge from the mechanism onto the delivery table renders the means for holding the pawl out of engagement with the ratchet inoperative to permit the conveyer to be advanced whenever a signature is discharged.
- 25 5. In a signature stitching machine or the like, a delivery mechanism including a delivery table provided with a movable conveyer, means for discharging completed signatures onto the table and conveyer, pawl and ratchet means for intermittently advancing the conveyer and means for oscillating the pawl, 90 means normally holding the pawl out of engagement with the ratchet to prevent its movement by the pawl to advance the conveyer, and means actuated upon the discharge of a signature to render inoperative the means normally holding the pawl out, whereby the conveyer is advanced.
- 30 6. In a signature stitching machine or the like, a delivery mechanism, including a delivery table provided with a movable conveyer, means for discharging completed signatures onto the table and conveyer, means for intermittently advancing said conveyer and drive means for the advancing means, and means for adjusting the time of operation of 95 said drive means with respect to the operation of the means for discharging the signatures, whereby the advance of the conveyer may be coordinated with the discharge of the signatures.
- 35 7. In a signature stitching machine or the like, a delivery mechanism including a delivery table provided with a movable conveyer, means for discharging completed signatures onto the table and conveyer, drive means for advancing the conveyer, means for driving the discharging means, means for adjustably connecting the drive means for intermittently moving the conveyer and the drive means for the discharge means, whereby the operation of the first-mentioned drive means may be coordinated with the discharge of signatures.
- 40 8. In a signature stitching machine or the like, a delivery mechanism including a delivery table provided with a movable conveyer, means for discharging completed signatures onto the table and conveyer, means for driving the conveyer, means for regulating the time of operation of said drive means, 100 and means for adjusting the degree of travel of said drive means.
- 45 9. In a signature stitching machine or the like, a delivery mechanism including a delivery table provided with a movable conveyer, means including a rotary drum for discharging completed signatures onto the table and the conveyer, means for driving the conveyer and means normally in contact with said drum for controlling the conveyer drive 105 means, whereby the conveyer is advanced upon a signature passing between the control means and the drum.
- 50 10. In a signature stitching machine or the like, a delivery mechanism, including a delivery table provided with a movable conveyer, means for discharging signatures onto the table and conveyer, means for intermittently driving the conveyer, a single member having means for regulating the time of operation of said drive means, and means for setting the degree of operation of said drive means.
- 55 11. In a signature stitching machine or the like, a delivery mechanism having a delivery 110
- 60 12. In a signature stitching machine or the like, a delivery mechanism including a delivery table provided with a movable conveyer, means for discharging completed signatures onto the table and conveyer, means for intermittently driving the conveyer, a single member having means for regulating the time of operation of said drive means, and means for setting the degree of operation of said drive means.
- 65 13. In a signature stitching machine or the like, a delivery mechanism having a delivery 115

table provided with a movable conveyer, means for discharging signatures onto the table and conveyer, means including a reciprocating pitman for driving the conveyer to intermittently advance the same, a driving disc for reciprocating the pitman, means for rotating the driving disc, and means for adjustably connecting the driving disc with its rotating means whereby the time of operation of said conveyer drive may be adjusted.

12. In a signature stitching machine or the like, a delivery mechanism having a delivery table provided with a movable conveyor, means for discharging signatures onto the table and conveyor and means including a reciprocating pitman for intermittently driving the conveyor, a rotatable driving disc for reciprocating the pitman, means for driving the driving disc, said means having a fixed relation to the means for discharging the completed signatures, means for adjustably connecting the driving disc with its driving means whereby the time of operation of the driving means for the intermittently advancing conveyer may be coordinated with the means for discharging the signatures.

13. In a signature stitching machine or the like, a delivery mechanism having a delivery table provided with a movable conveyer, means for discharging completed signatures onto the table and conveyer, means including a pawl and ratchet for intermittently driving the conveyer, means including a rotating member for oscillating the ratchet, means for holding the pawl out of engagement with the ratchet to prevent advancement of the conveyer, means carried by the rotatable member for moving the pawl holding means to its operative position, means for maintaining the pawl holding means in operative position, and means movable by the passage of a signature during its discharge onto the delivery table for rendering said maintaining means inoperative.

14. In a signature stitching machine or the like, a delivery mechanism including a delivery roll, pulleys and an endless member trained over the pulleys and delivery roll for carrying signatures outwardly from the machine, means for adjusting the location of the outermost of the pulleys with respect to the delivery roll to accommodate signatures of different sizes.

15. In a signature stitching machine or the like, a delivery mechanism including a delivery roll, pulleys and an endless member trained over the pulleys and delivery roll for carrying signatures outwardly from the machine, that portion of the endless member running from the delivery roll to the outermost of said pulleys providing a guide for discharged signatures, and means for adjusting the angle of said guide with respect to the horizontal.

16. In a signature stitching machine or the

like, a delivery mechanism including a rotatable delivery roll, pulleys and an endless member trained about the pulleys, one of which is disposed above and outwardly with respect to the delivery roll, said member cooperating with the delivery roll to discharge completed signatures from the machine, and means for adjusting the position of the pulley disposed above and forwardly with respect to the delivery roll.

17. In a signature stitching machine or the like, a delivery mechanism including a delivery roll and an endless member trained over the delivery roll cooperating therewith to discharge completed signatures from the machine and pulleys about which the endless member is trained, the stretch of the endless member between the delivery roll and one of the pulleys governing the angle of discharge of the signatures, means for adjusting the angle of inclination of the said stretch of the endless member to accommodate signatures of different characteristics.

18. In a signature stitching machine or the like, a delivery mechanism, a delivery roll, a plurality of idlers, an endless member traveling about the idlers and trained over a portion of the delivery roll and cooperating therewith to discharge completed signatures from the machine, the stretch of the endless member between the delivery roll and the outermost of said idlers forming means for directing the discharge of the signatures and the point of tangency of said stretch of the endless member with the delivery roll governing the angle of the signature discharge, and means for adjusting the location of said point of tangency whereby the angle of discharge of signatures is readily adjustable to accommodate signatures of different characteristics.

In testimony whereof I have hereunto affixed my signature.

ELMER W. BELLUCHE.
